UNITED STATES PATENT OFFICE

JOHN K. HARFORD, OF LEWISTON, IDAHO

FLUID-PRESSURE-OPERATED MOTOR

Application filed December 18, 1928. Serial No. 326,777.

My present invention relates to an improved fluid pressure operated motor, which while adapted for various uses is especially designed for the purpose of controlling the flow of water for sprinkling purposes. In the construction of concrete and cement streets and roads, as is well known, it is desirable and necessary that the completed way be sprinkled at intervals with water to insure 10 the proper completion of the roadway or street before it is used for traffic.

The motor of my invention contemplates the employment of a fluid operated device or apparatus having a main pipe that is attached 15 to the water supply system to receive its supply of water, and a system of distributing pipes with sprinkling nozzles is also attached to the apparatus. The distributing nozzles may be located at points along the finished 20 street surface so that the entire surface may be sprinkled simultaneously and at regular and uniform intervals as desirable or necessary, and means are provided in the motor apparatus for automatically opening and 25 closing a main control valve that governs the flow of water from the supply system to the sprinkling system.

The motor is of that type using a cylinder and water operated piston, the water being 30 supplied to the motor under pressure from the street main, and the main valve, together with other valves necessary for the operation of the mechanism are operated by mechanisms actuated from the stem of the piston.

The invention consists in certain novel 35 combinations and arrangements of parts as will hereinafter be more fully set forth and claimed.

In the accompanying drawings I have illustrated one complete example of the physical embodiment of my invention wherein the parts are combined and arranged according to the best mode I have thus far devised 40 for the practical application of the principles of my invention, and which embodiment has been successfully operated. Various changes and alterations within the scope of my claims may be made in the exemplified structure, and the motor and connections may be 45 adapted for various other uses.

Figure 1 is a view in side elevation of an appliance embodying my invention, the parts being shown in position with the main control valve open, and in dotted lines showing some parts in closed position. 55

Figure 2 is a view in elevation as seen from the left in Figure 1, with dotted lines showing some of the parts in closed position for the main valve.

Figure 3 is a sectional detail view of the 60 cylinder and its plunger or piston.

Figure 4 is a perspective view of the appliance.

In carrying out my invention I utilize a main pipe 1 of suitable diameter and length, 65 which is provided at one end with a coupling 2 that is attached to the usual water supply pipe, and at its opposite end this pipe is provided with a faucet 3 and threaded nipple 4. By means of a hose and coupling the nipple 4 70 is connected to the street sprinkling pipes, and the latter are provided with the sprinklers distributed at regular intervals, or where desired, for sprinkling water to the work.

An upright cylinder 5 supported on legs or 75 feet 6 is utilized as the water pressure chamber, and a main supply or control valve 7 is interposed in the pipe 1, and periodically opened and closed by mechanism operated from movement of the piston or plunger 9 in 80 the cylinder or reservoir. The piston is adapted to reciprocate under water pressure in the reservoir or cylinder, and the supply valve 7 remains open for flow of water 85 through pipe 1 while the piston is rising and remains in uplifted position of Figure 3. When pressure of water is released from the under side of the piston and applied at the upper side of the piston, the latter falls, and during the descent of the piston the main 90 supply valve 7 is closed. A by-pass pipe 8 is connected to the lower end of the cylinder.

The piston has an upright stem 10 projecting through a stuffing or packing box 11 at the top of the cylinder, and a piston rod 13 95 is rigidly connected with the stem by a bracket 14 at the complementary upper ends of the stem and rod. The rod extends downwardly exterior of the cylinder and is adapted to reciprocate in the guide brackets 13' supported 100

from the cylinder near the upper and lower ends thereof, and of course the rigid stem and rod ascend and descend in unison.

A bracket 15 is fixed at the top of the cylinder and projects thereabove for the support of a floating link 16 that is pivoted at 17 in the upper end of the bracket, and this floating lever or link is designed to swing in a vertical plane on its pivot as indicated by dotted lines and full lines in Figure 1. At the free, outer end of the floating link an upright lever 18 is pivoted, and a snap spring 19 is suspended between the piston rod and the free end of the link. It will be apparent that as the rod rises and falls it carries with it the spring, and as the rod-end of the spring passes the pivot 17 a snap action is given to the floating link 16 to raise or lower it. This snap movement is imparted to the valve lever 18, and the latter is pivoted at the free end of a valve lever arm 20, which at 21 is pivoted to the main supply valve 7 for opening and closing the valve.

The range of the opening and closing movements of the lever arm 20 is indicated by dotted and full lines in Figure 2, the valve being open for the flow of water when the lever arm is up, and closed against flow of water when the lever arm is snapped by the snap action down to dotted position.

In the by-pass pipe 8 which connects the main pipe 1 with the lower end of the cylinder, below the piston, and supplies the water pressure for elevating the piston, is interposed a drain valve 22, which, when open drains water from the upper or working portion of the cylinder, below the piston. This drain valve is automatically closed when the water is flowing through the main supply valve, and is automatically opened when the water is cut off by the closing of the main valve 7.

For the operation of the drain valve 22 a link 23 is pivoted on the lever arm 20 of the main valve, and the link 23 is pivoted at the free end of the drain-valve lever arm 24 which is connected to the rotary stem 25 of the drain valve for operating the latter.

A water pressure pipe 26 extends from the main pipe 1 behind the main valve to the upper portion of the cylinder and enters the cylinder above the piston 9 for supplying water pressure on the piston to force it downwardly to initiate the closing movement of the main valve 7. This water pipe also has a valve as 27 that is automatically opened and closed through power transmitted from the moving piston rod 13 and valve operating lever 18, through the valve lever arm 20. When the main valve is closed this control valve 27 is also closed, and of course both valves are simultaneously opened, the control valve being actuated from the lever arm 20 by means of lever arm 28 and link 29, the latter

being connected with the valve 27 for its operation.

Two manually operated regulating valves 30 and 31 are provided in the water pressure pipes 8 and 26 respectively, by means of which the volume and pressure of water passing to the cylinder may be controlled, the former to govern the period of time that the water is "on" and flowing through the main valve, and the latter to govern the period of time the water is "off" with the main valve closed.

Assuming the street is to be sprinkled at predetermined half-hour intervals for sprinkling periods of say five minutes, the regulating valve or time valve 30 is set to permit flow of such a quantity and pressure of water through pipe 8 as will lift the piston in a half hour, and the regulating valve 31 is set to permit flow of water for five minutes while the cylinder is draining from below the piston. The main valve 7 is thus opened and remains opened for five minute intervals at the end of every half hour period of time.

When the piston reaches the upper end of its stroke the spring 19 is snapped and the main valve is closed; drain valve 22 is opened to drain the water from the cylinder past the main valve or in front of it; and control valve 27 is opened back of the main valve to permit water pressure to flow into the top of the cylinder for lowering the piston. At the lower end of the piston stroke the positions of the automatically operated valves are changed by the spring action, and these successive actions take place as long as the pressure exists in the main pipe 1 of the appliance.

Having thus fully described my invention, what I claim as new and desire to secure by Letters Patent is—

1. In a fluid pressure operated sprinkling system the combination with a main pipe and a main supply valve therein, of a cylinder and piston therein, pressure pipes from the main pipe to the cylinder at opposite sides of the piston and control valves in said pipes, operating mechanism for the supply valve connected to and operating with the reciprocating movement of the piston, and valve operating mechanism for the control valves actuated by the first valve-operating mechanism.

2. In a fluid pressure operated sprinkling system, the combination with a main pipe and a supply valve therein, of a cylinder and reciprocating piston, pressure pipes connecting the main pipe at opposite sides of the main valve with the ends of the cylinder, control valves in the pressure pipes, and valve operating mechanisms actuated from the piston for all of said valves.

3. In a fluid operated pressure sprinkling system, the combination with a main pipe and supply valve therein, of a cylinder and its reciprocating piston, pressure pipes con-

necting the main pipe at opposite sides of the main valve with the ends of the cylinder, valves for regulating the flow of water through said pressure pipes, control valves in the pressure pipes, and operating mechanism actuated from the piston for said main valve and control valves.

4. In a fluid pressure operated sprinkling system, the combination with a main pipe and its valve and a pressure-operated reciprocable member, of a valve lever and lever arm and a floating link connected with the valve lever, and a snap spring connecting said member and the free end of the link, for the purpose described.

5. In a fluid pressure operated sprinkling system, the combination with a main pipe and its supply valve, a cylinder and piston therein, of water pressure pipes connecting the main pipe at opposite sides of the valve with the ends of the piston, control valves and manually operated regulating valves for said water pipes, a piston stem and piston rod rigid with the piston, a floating link having a pivotal support and a snap spring connecting the free end of the link with the rod, and valve operating mechanisms for the main valve and control valves connected with the link.

30 In testimony whereof I affix my signature.

JOHN K. HARFORD.
